UNITED STATES PATENT OFFICE.

ASHBY A. SHAW AND RALPH A. STEVENS, OF CAMBRIDGE, MASSACHUSETTS.

MEANS FOR PRODUCING DENTAL AMALGAM.

SPECIFICATION forming part of Letters Patent No. 715,216, dated December 2, 1902.

Application filed April 22, 1901. Serial No. 56,809. (No model.)

To all whom it may concern:

Be it known that we, ASHBY A. SHAW and RALPH A. STEVENS, citizens of the United States, residing at Cambridge, in the county 5 of Middlesex and State of Massachusetts, have invented certain new and useful Improvements in Means for Producing Dental Amalgam, of which the following is a full, clear, and exact description.

10 In the production of dental amalgam by a dentist for his own use we have found the best method to be to mount a mass of the solid alloy upon the spindle of a lathe and to turn off the required quantity of powder and particles from such mass in the usual manner.

15 The object of this invention is the construction of an improved means for enabling the mass of solid alloy to be conveniently mounted upon a spindle.

20 To this end our invention comprises two related elements—a mold for enabling the mass of alloy to be cast upon a spindle and a spindle adapted to be applied to and removed from the mold.

25 Referring to the drawings forming part of this specification, Figure 1 is a vertical central section of our mold, showing the spindle supported therein. Fig. 2 is a horizontal section of the same; and Fig. 3 is a longitudinal 30 sectional view of the spindle and parts carried thereby, showing it as supported in bearings and having a driving-pulley mounted thereon, the pulley and bearings being shown in section.

35 As shown in Fig. 3, the spindle 10 is terminally supported in bearings 20 and rotated by the pulley 16, mounted friction-tight thereon. Upon this spindle is rigidly secured the cylindrical body of alloy 15, from the periphery 40 of which is turned the powder of shavings to be used in the formation of what is termed "dental amalgam." To mount the body of alloy upon the spindle, we have devised the mold, which comprises the cylindrical shell or body 45 1, having a flat bottom 2 and a removable cover 6. Centrally through said bottom and cover are the openings 3 and 9, the opening through the cover fitting the main portion of the spindle, while the opening through the 50 bottom is fitted to the reduced end 12 of the spindle. The bottom of the mold is raised a short distance by means of the flange 4 in or-

der to keep the spindle-point 11 from resting upon the support for the mold. The cover 6 is formed with a flange or rim 7, fitting about 55 the rabbeted edge of the mold-body, not only for the purpose of keeping such cover in place, but mainly to retain the opening 9 concentric with the mold-body 1, and thus accurately determine the central position of the 60 spindle in the cylinder of alloy. Through the cover is formed a tunnel-shaped passage 8 for permitting the melted metal to be poured into the mold. Through much of the spindle's length is cut a groove or spline 14, designed 65 to receive the melted alloy, and thereby hold the latter when solidified securely in place on the spindle. At the end of the spindle opposite to the reduced end 12 is a tapered section 13, designed to enter a correspondingly-tapered hole in the pulley 16. By means of this taper the pulley can be readily applied to and removed from the spindle, and yet when applied to the spindle grip the same with sufficient tightness to enable the pulley 70 to turn the spindle, and hence the solid alloy mounted thereon. The object in thus having the pulley removable is as follows: Although the spindle can be readily introduced through the opening in the cover down into 75 the mold, even when the pulley is in place thereon, yet the presence of the pulley prevents the convenient entrance of the melted metal through the passage or mouth 8. Moreover, after the metal has been poured within 80 the mold and has hardened about the spindle the cover 6 cannot be removed until after the pulley has been itself removed. For these reasons, therefore, we have the pulley removable in the first instance.

85 By means of our arrangement of spindle and pulley and our construction of mold we are enabled to quickly, conveniently, and accurately cast a mass of solid alloy upon the spindle and apply the latter to the lathe, by 90 which the metal is converted into powder and shavings with the least possible trouble and loss of time.

95 What we claim as our invention, and for which we desire Letters Patent, is as follows, 100 to wit:

In a means for applying cylinders of metal to spindles of the character described, the combination with the cylindrical mold con-

sisting of the integral sides and bottom, of the cover fitted to the open top thereof and having the central opening constructed to loosely receive said spindle, and the pouring-hole; 5 said mold-bottom having the central hole less in diameter than the central opening in said cover, and the under side of said bottom being formed with the supporting-flange, substantially as described.

In testimony that we claim the foregoing 10 invention we have hereunto set our hands this 17th day of April, 1901.

ASHBY A. SHAW.
RALPH A. STEVENS.
